(57) **CLAIM**

The ornamental design for a panorama window bag, as shown and described.

DESCRIPTION

FIG. 1 is a front perspective view of a panorama window bag according to my new design;

FIG. 2 is a plan front view thereof;

FIG. 3 is a plan back view thereof; and,

FIG. 4 is a cross-section view thereof taken along line 4—4 of FIG. 3.

The broken lines are shown herein for illustrative purposes of the environment and form no part of the claimed design.
